UNITED STATES PATENT OFFICE.

ADOLPH GRONLUND, OF STOCKHOLM, MAINE.

FILLING MECHANISM.

1,410,097.

Specification of Letters Patent. Patented Mar. 21, 1922.

Application filed August 8, 1921. Serial No. 490,525.

To all whom it may concern:

Be it known that I, ADOLPH GRONLUND, a citizen of the United States, residing at Stockholm, in the county of Aroostook and

5 State of Maine, have invented certain new and useful Improvements in Filling Mechanism, of which the following is a specification, reference being had to the accompanying drawings.

10 This invention relates to filling mechanisms and has for an important object thereof the provision of a device whereby solid materials may be deposited in a plurality of receptacles, the discharge into each receptacle being discontinued when the receptacle has received a predetermined amount.

15 A further object of the invention is to provide a device of this character wherein the materials placed in the receptacles are positively directed into the receptacle.

20 A still further object of the invention is to provide a chute for delivering materials to a plurality of receptacles, the chute embodying tilttable sections arranged over each receptacle or series of receptacles which tilt when the first series of receptacles has been filled to cause the delivery of the material from the chute into a second set of receptacles.

25 Further objects of the invention will appear as the following specific description is read in connection with the accompanying drawings which form a part of this application and in which:

30 Figure 1 is a side elevation with the inner side plate removed so as to more clearly show the arrangement of the parts, the parts being shown in elevation;

35 Figure 2 is a similar view taken from the opposite side of the machine with the inner side plates attached;

40 Figure 3 is a section taken on the line 3—3 of Figure 1;

45 Figure 4 is a similar view taken on the line 4—4 of Figure 1;

50 Figure 5 is a section taken on the line 5—5 of Figure 1; and

55 Figure 6 is a detail longitudinal section showing the method of tripping the platform sections.

Referring more particularly to the drawing, 1 and 2 represent side bars which are connected together by the bottom 3 and which have rising therefrom the uprights 4, 5, 6 and 7 to which are attached the side plates 8, 9 and 10.

The parts thus described form what may be termed the body of the machine which is mounted upon wheels 11 keyed to the axle 12 which is journaled in bearings 13 mounted upon the under side of the side bars 1 and 2. The wheels 11 are preferably provided with traction surfaces, as shown, and support the major portion of the machine. The front of the machine is supported by 60 caster wheels 14 carried upon stub shafts 15 extended from the vertically disposed mounting rods 16 which operate through bearings 17 in the side bars 1 and 2, and have secured thereto the collars 18 between 70 which and the bracing bracket 19 is located a spiral spring 20 which takes up any shocks but permits rotation of the shaft 16 as the machine is turned to follow the digger.

75 Extending across the machine and journaled in the uprights 5 is a shaft 21 having secured at opposite ends thereof the sprocket wheels 22 which are connected to similar sprocket wheels 23 on the shaft 12 by a 80 sprocket chain 24. The shaft 21 also has secured thereto sprocket wheels 25 arranged at opposite ends and connected by means of the sprocket chain 26 to the sprocket wheels 27 secured upon the crank shaft 28, the purpose of which will be hereinafter described. At one side of the machine the shaft 21 has secured thereto a pulley 29 connected by a cross belt 30 to a similar pulley 31 arranged upon one end of a shaft 32 journaled in bearings upon an extension 33 which projects horizontally from adjacent the outer ends of the uprights 4.

85 The shaft 32 carries sprocket wheels 34 which are connected by means of the chains 95 35 to similar sprocket wheels 36 keyed to a shaft 37 which is journaled in bearings upon the under side of the side bars 1 adjacent their forward end. These chains carry suitable transversely disposed flights or conveyor buckets 38 which, when loaded, rest upon the supporting board 39 inclined from the upper surface of the side bars 1 to the extension 33. At the forward end of the side bars 1 I provide a transversely extending scoop or receiver member 40 adapted to receive the potatoes from the digger, as will be hereinafter more fully understood, and to convey them to the flights or buckets 38.

100 105 110 The shaft 28 is, as shown in Figure 3, provided with a plurality of cranks 41, each of

which is connected to similar cranks 42 on a shaft 43 which is journaled in bearings carried by brackets 44 mounted on the uprights 4 by a bar 45. These bars, as shown, are 5 rounded upon their upper face and flat upon their lower face and by the action of the cranks are caused not only to reciprocate back and forth but up and down, as will be readily understood. They receive the potatoes from a short inclined platform 46 and 10 separate from the potatoes all soil and small stones which fall on the upper surface of a double chute 47 leading to openings 48 in opposite sides of the machine so that all soil 15 and stones separated are dumped back upon the field.

All potatoes passing from the shaking bars 45 drop upon a screen 49 which is pivoted to the uprights 6, as at 50 and has 20 its opposite end connected to the crank 51 formed on the shaft 21. This screen is slightly angular in cross section so that when in its uppermost position it will have a substantially level portion 52 and an inclined portion 53. The screen 49 is provided 25 to separate all small potatoes from the large potatoes and in order to save these small potatoes which are passed through the screen, I provide an inclined chute 54 arranged immediately below the screen and 30 between the uprights 5 and 6 and adapted to direct the small potatoes into a box or other container 55 removably positioned between the uprights 4 and 5. The large potatoes 35 which are discharged by the screen 53 fall upon a platform 56 which is secured rearwardly of the uprights 6 between the side bars 57 connected to the upper ends of the uprights 6 and 7 at the sides of the machine, 40 as shown in Figure 5. Extending across and secured to shafts 58 journaled in the side bars 57 are platform sections 59, each of which is provided with oppositely disposed segments 60 secured to the ends of the platform sections, as shown in Figure 1. Each 45 of the segments 60 is provided with an inwardly extending stud 61 at one side of the shaft 58 of its associated section, and pivoted to the side plate 10 immediately beneath the stud of each section is a latching lever 62 having an offset and depending end 63 which enters a barrel 64 to be filled. The upper end of the latching lever is provided with 50 a hook 65 adapted to engage over the stud and hold the section 59 in horizontal position. For each segment I secure to the side plate 10, at one end, a contractile spring 66, whose opposite end is connected to the segment on the opposite side of the shaft 58 55 from the stud, so that when the hook 65 is released from the stud, the spring will act to throw the section to a vertical position, as indicated in Figure 1.

60 Journalized in suitable bearings on the under side of the side bars 1, at separated

points, are the shafts 67 and 68, each of which carries sprockets 69 connected together by chains 70 on opposite sides of the machine. The shaft 67 also carries a sprocket 71 which is in turn connected by 70 a chain 72 to an operating sprocket 73 journaled upon a stub shaft 74 and carrying a crank 75. Each of the shafts 67 and 68 carries, intermediate the side bars 1, suitable rollers or drums 76 upon which is mounted 75 a slatted conveyor 77 preferably resting upon or sliding over the bottom 3, as will be readily understood. Any suitable anti-friction means, not shown, may be interposed between the slats of the conveyor and the bottom in order to insure free operation of the conveyor. All barrels to be filled are mounted upon the conveyor, as shown in Figures 1 and 5, and the rows of barrels may contain as many as is found desirable 80 in practice, the two end or side barrels each having the offset or depending ends 63 of the levers 62 placed therein so that when the potatoes being discharged into the barrel fill the same, they will contact with the ends 85 63, throwing them to the position shown in dotted lines in Figure 6, and releasing the hooks 65 from the studs and permitting the spring 66 to throw the section to the position shown in dotted lines in Figure 6, which 90 prevents any more potatoes being discharged into the end row of the barrels. The sectional platform then terminates at the end of the adjacent section 59, and the potatoes are discharged from the end of said section 95 into the next row of barrels where the operation is repeated. When all of the barrels have been filled, the machine is stopped and the operator turns the crank 75 toward him which moves all of the barrels outwardly. The bottom of the machine is of a height equal to the height of the bed of a wagon so that the barrels may be discharged right on to the wagon bed and then conveyed away. After all the filled barrels have been 100 removed, new empty barrels are placed in position on the conveyor, and by rotating the handle away from the operator, may be placed in proper position beneath the sections, it being understood of course that the 105 latch levers are turned out of the way first to permit their proper entrance into the barrels when the barrels are properly positioned beneath the sections.

From the foregoing it is thought that the 110 operation of the machine will be readily understood. I, however, desire to state that the digger employed may be any suitable type, and is so connected to the machine that it will dump the potatoes on to the member 115 40 from which they are picked up by the flights or buckets 38 of the conveyor and then conveyed, as has been previously described, to the shaking bars 45 over the platform 46. It will thus be seen that I have pro- 130

vided a machine which will take the potatoes from the digger and separate therefrom all stones and soil and then sort the small potatoes from the large potatoes, after which the 5 machine will automatically fill a plurality of barrels carried thereon, and as each set of barrels is filled, will automatically act to cut off the supply to that set of barrels and discharge the potatoes into another set.

10 What I claim is:

1. A filling mechanism comprising a plurality of pivoted sections independently shiftable about the pivots thereof to combine with the remaining sections to form a 15 chute for delivering material or a baffle checking the flow of material along the chute formed by the remaining sections, and means for moving each of said sections to the last named position operable when a 20 predetermined amount of material has passed thereover.

2. A filling mechanism comprising a plurality of pivoted sections independently shiftable about the pivots thereof to combine with the remaining sections to form a 25 chute for delivering material or a baffle checking the flow of material along the chute formed by the remaining sections, means for moving each of said sections to 30 the last named position, and material releasable means for locking the sections

against movement under influence of the last named means until a predetermined amount of material has passed thereover.

3. A filling mechanism comprising a plurality of pivoted sections independently shiftable about the pivots thereof to combine with the remaining sections to form a chute for delivery of material or a baffle checking the flow of material along the chute 40 formed by the remaining sections, a spring 35 engaging each of said sections and tending to move the same to the last named position, and a latch locking each section against movement under the influence of its spring 45 and withdrawn by the engagement of the material therewith when a predetermined amount of material has passed over the section.

4. A filling chute comprising a plurality of independently tiltable sections, each section when tilted forming a baffle 50 limiting the movement of material passing over the discharge end of the chute, and means rendered operative by the passing 55 of a predetermined amount of material over the discharge end of the chute for tilting the section forming the discharge end to form a baffle.

In testimony whereof I hereunto affix my 60 signature.

ADOLPH GRONLUND.
